UNITED STATES PATENT OFFICE

BYRON R. BARDER, OF AKRON, OHIO, ASSIGNOR TO THE BIGGS BOILER WORKS COMPANY, A CORPORATION OF OHIO

HEATING APPARATUS

Application filed August 19, 1926. Serial No. 130,301.

This invention is directed to an improved apparatus for agitating and heating a fluid mass within a retort, and has particular reference to the treatment of rubber or rubber goods, as in devulcanizing, reclaiming, refining, dissolving and similar processes.

Prior to this invention, devulcanizers and the like have included an inner main shell, usually of cylindrical form providing a retort within which the material to be treated is placed with an alkaline or acid solvent. Surrounding the main shell and in spaced relation thereto is an outer shell forming a steam jacket by means of which the material within the retort may be heated, said inner and outer shells being firmly secured together by stay-bolts, rivets and the like in order to overcome collapsing and bursting pressures. The use of stay-bolts and other bracing means, besides being costly is objectionable for other reasons, preventing the independent expansion and contraction of the inner and outer shells, and frequently causing leakage and other disadvantages. The disposition of the heating jacket outside the retort has also given rise to objections, because such arrangement results in substantial heat losses through radiation and lack of uniform heating of the mass of material within the retort.

These and other serious objections of the prior art are overcome by the present invention which contemplates the treatment of the rubber material by heat applied internally of the mass. To this end, the retort instead of being equipped with the usual steam jacket, is provided with an internal heating drum which is of such proportions as to present a substantial heating surface to the material contained within the retort. The heating drum not only is capable of standing extreme high pressures such as are frequently desired, but is free to expand and contract independently with respect to the main casing, thereby avoiding the difficulties inherent in the prior jacketed stay-bolt construction above referred to. Moreover, since the drum is completely inclosed within the mass of material all of the heat generated in the drum is caused to permeate

the entire mass from within, thus producing a more efficient and uniform heating of the stock, and also avoiding the external and radiation heat losses so characteristic of the prior jacketed construction.

Another feature of the invention resides in the provision of means for rotating the heating drum, and in the provision of internally heated paddles carried thereby to assist in the agitation of the mass.

These and other features and advantages will readily appear from the following description, when taken in connection with the accompanying drawings, wherein the invention is shown merely by way of illustration.

In the drawings Figure 1 is a vertical, longitudinal sectional view through one type of devulcanizer embodying the invention;

Figure 2 is a transverse sectional plan view taken on the line 2-2 of Figure 1;

Figure 3 is a detail sectional view through one of the paddles, said section being taken on the line 3-3 of Figure 2;

Figure 4 is a sectional view similar to Figure 2, but on a smaller scale, illustrating a modified form of paddle carried by the heating drum;

Figure 5 is an elevation of said modified form of paddle; and

Figure 6 is a detail, sectional view on line 6-6 of Figure 4.

In Figures 1 to 3, a devulcanizer of vertical type has been shown embodying a main shell or casing 10, preferably of cylindrical form and fitted with upper and lower head portions 11 and 12 secured to the main body portion by riveting, welding or the like, to form a vessel or retort with an enclosed treating chamber 13.

Adjacent its lower end, the casing 10 is provided with a central bearing member 14 supported by a plurality of radial arms 15 secured to a mounting ring 16 having a floating fit with the casing 10.

The upper head 11 is centrally apertured as at 17 and fitted with a bearing member 18 in axial alignment with the bearing member 14. Arranged within the bearing member 18 is a hollow rotatable shaft 19 whose lower end extends downwardly into the re-

retort chamber 13 and whose upper end extends above the bearing member 18. In order to prevent leakage from the retort, the bearing member 18 is fitted with a stuffing box 20 for the reception of any suitable packing material, which may be compressed by a packing gland 21. The upper head 11 is further provided with a bracket 22 having a laterally extending arm 23 through which the hollow shaft 19 also extends, said arm 23 forming a thrust bearing for the support of a bevel gear 24 which is secured to the shaft 19 by a set screw 25 or other suitable fastening means. Thus the weight of the shaft 19 and its associated parts is substantially supported by the arms 23 supplemented by buoyancy as will be hereinafter described. Below the bearing member 18, the shaft 19 is fitted with a thrust collar 26, and depending from the shaft 19 is a heating drum designated generally by the reference character 27.

The heating drum 27 comprises a rotary hollow cylindrical member 28 which represents a substantial heating surface for contact with the material within the retort chamber 13, and which is held against lateral movement adjacent its lower end by the central bearing member 14 before referred to. At its upper end, the cylindrical member 28 is fitted with a cap 29 by means of which it is secured to the inner or lower end of the shaft 19 as at 30, while at its lower end the member 28 is closed by a cup-shaped plug 31, the proportions of the parts being such that said plug 31 is spaced from the inner surface of the lower head 12 of the main casing. By reason of such spacing and the floating fit of the mounting ring 16, the heating drum is capable of relative longitudinal movement with respect to the main casing, and therefore said parts are free to expand and contract independently under the different temperatures to which they are subjected.

In order to conduct a heating medium, such as steam or hot water, to the interior of the drum 27, the upper extremity of the hollow shaft 19 is equipped with a swivel pipe connection 32 and packing gland 33, said swivel connection 32 being in communication with the central bore 34 of shaft 19, and being supplied with the heating medium through an inlet pipe 35 from any suitable source of supply. An exhaust pipe 36 is employed to insure complete circulation of the heating fluid, said pipe 36 being of a smaller diameter than the interior of the swivel connection 32 and bore 34, and extending upwardly through said parts from a point near the bottom of the drum 27.

Meshing with the bevel gear 24 is a bevel pinion 37 on a shaft 38, which has a bearing at 39 in the bracket 22, and further provided with a pulley 40 or the like for the applica-

tion of power. Thus the gears 37 and 24 may be operated to rotate the drum 27.

It is desirable to agitate the material within the retort chamber, while it is being treated, and to this end the drum 27 carries a plurality of paddles extending radially therefrom toward the cylindrical wall of the main casing 10. The paddles may be conveniently formed from lengths of pipe 42 which extend diametrically through the cylindrical member 28, three of such pipes being shown in the drawing, and each having its opposite ends closed by suitable caps 43. Intermediate of their ends, the pipes 42 are formed with apertures 44 whereby the heating fluid from within the drum 27 may also be circulated through said pipes. The agitation of the mass of material in the retort may be further facilitated by the application of relatively flat plates 45 which may be secured to the pipes by means of U bolts 46 and clamping nuts 47, as best shown in Figures 2 and 3. The plates 45 are preferably disposed at an angle at the front side of the pipes 42 with respect to their direction of rotation, and in this manner they will have a churning and cutting tendency in their operation. The agitation of the mass may be further insured by the use of propeller blades 48 secured to the plug 31 at the lower end of the drum 27, said blades tending to force the material upwardly as they are rotated.

The main casing 10 may be mounted on any suitable foundation by means of supporting brackets 49, and access may be had to the interior of the treating chamber 13 through a manhole 50, normally closed by a closure plate 51, stud 52, and yoke 53. After the process has been completed, the material from the treating chamber 13 may be removed through a drain pipe 54 in the lower head portion 12.

In using the above described apparatus for carrying out my improved process, the waste material to be treated is inserted in the chamber 13 with a suitable alkaline or acid solvent, as is well known to those skilled in the art. The material is preferably ground or cut into relatively small pieces in order that it may be more uniformly acted upon by the solvent. The heating fluid, preferably steam, is then admitted to the drum 27 through the inlet pipe 35 and thereafter the drum 27 is rotated by the application of power to the pulley 40, such power being transmitted by the gears 37 and 24 to the hollow shaft 19. As the drum 27 and its attached agitators 42 and 45 are thus rotated within the mass of material, said material is thoroughly churned and agitated, with the result that it becomes uniformly heated throughout its entire body, greatly facilitating the devulcanization of the rubber. Both the drum 27 and the pipes 42 provide a closed circulating system for the heating

fluid, so that it is prevented from coming in direct contact with the material undergoing treatment. It is to be noted that the heating drum 27 presents a substantial heating surface, and that the heat generated in the drum will penetrate outwardly through the entire mass of material. It will also be evident that, due to the proportions of the drum 27, the weight supported by the bearing arm 23 will be somewhat relieved by the buoyancy of the supported parts, and, furthermore, that the heating drum 27 is free to expand longitudinally independently of the main casing 10. After the material has been so treated for the proper length of time, the rotation of the drum and paddles may be stopped and the resultant mixture withdrawn from the chamber 13 through the drain pipe 54, for further treatment in the usual manner to separate the reclaimed rubber.

It has been found that the application of heat to the material internally results in a more uniform heating and produces a higher quality of reclaimed rubber, and this feature is additionally advantageous in that it reduces heat losses by radiation to a minimum. Furthermore, the heating drum 27, being of considerably smaller diameter than the prior art heating jackets, is capable of withstanding increased internal pressures without necessitating an undue thickness of metal and without requiring stay-bolts or other bracing means for reinforcement. Thus when steam is used as the heating medium, the higher pressure results in higher temperatures, reducing the time necessary for completion of the process as compared with the prior art apparatus of the jacketed type.

Having thus described my invention, what I claim is:

A devulcanizing apparatus including in combination, a container for the material to be treated, a steam-tight, hollow, heating drum having radial hollow arms communicating therewith and forming a heat circulating element adapted to heat to devulcanizing temperature the entire mass of material within the container, said drum being rotatably suspended from the top of the casing and having a clearance from the bottom thereof, blades angularly arranged on said hollow arms, whereby the mass of material will be churned and crushed and heated throughout to devulcanizing temperature, means for rotating said drum, an outlet pipe arranged in the drum for the water of condensation, and an outlet for the treated material.

In testimony whereof, I have affixed my signature hereto.

BYRON R. BARDER.
